MAGNETO ROTOR

Curt F. Reis, New York, N. Y.; Adele Reis executrix of said Curt F. Reis, deceased

Application November 28, 1939, Serial No. 306,567

4 Claims. (Cl. 171—209)

The present invention relates to rotors for magnetos of the type employing permanent magnets, and has for its primary object to generally improve such structures.

A further object of the invention resides in the construction of a rotor in which the magnet extends transversely of the rotor shaft and has its major axis extending through the axis of the shaft.

A further object of the invention resides in providing a rotor with a sectional magnet, the sections of which may be formed of cast metal and yet which need not be machined to provide the required contact between the meeting faces of the sections.

Another object of the invention consists in binding together in intimate contact the sections of the magnet by the shrinkage of an aluminum or other metal jacket which partly surrounds the assembled magnet sections.

Another object of the invention resides in drawing laminations or pole shoes into intimate contact with the poles of the magnet by the shrinkage of a cast aluminum or other metal jacket on the rotor.

A further object of the invention consists in securing the laminations of each of the pole shoes in intimate contact with each other without the use of rivets, thereby avoiding the creation of eddy currents and correspondingly increasing the magnetic value of the magnet.

Another object of the invention consists in providing bulges on the exterior sides of the magnet sections so as to increase the mass of metal in the magnet without unduly increasing the diameter of the rotor, and thereby increasing the coercive force or magnetic value of the magnet.

A further object of the invention resides in a novel construction by which the body of the rotor is anchored or locked to the rotor shaft to prevent relative movement between these elements.

Other objects and advantages of the invention will be apparent from the following description when taken in connection with the accompanying drawing, in which,

Figure 1 is a perspective view of the rotor.

Figure 2 is a longitudinal sectional view thereof taken through the magnet.

Figure 3 is a transverse sectional view taken on line 3—3 of Figure 1.

Figure 4 is a longitudinal sectional view taken on line 4—4 of Figure 3.

Figure 5 is a perspective view of one of the sections of the magnet shown in Figures 1 to 4 inclusive, and

Figure 6 is a transverse sectional view through a rotor in which the pole shoe laminations have been omitted.

Referring to the drawing in more detail and particularly to Figures 1 to 5 inclusive, the numeral 1 indicates a conventional steel shaft on which the rotor parts are mounted and adapted to have its ends rotatably mounted in the casing of the magneto. Diametrically opposite portions 2 of the shaft are preferably flattened to provide interlocking connections with the rotor proper in a manner which will later appear.

The rotor depicted in Figures 1 to 5 inclusive is of the bipolar type, and the magnet which is generally indicated by the numeral 3 is mounted with its major axis passing through the axis of the shaft 1. The magnet 3 is composed of two sections 4 and 5 which are identical in form. These sections 4—5 are formed of cast metal and extend substantially the entire length of the rotor. It will be understood therefore that the magnet comprises a relatively large mass of metal and has a correspondingly high coercive force. Moreover, by reason of the fact that the sections 20 of the magnet are formed of cast metal it will be readily understood that the size of the magnet sections and likewise the magnetic volume may be easily varied to suit varying requirements. In the embodiment of the invention illustrated the outer faces of the magnet sections are provided with bulges 4' and 5' to increase the mass of the magnet and likewise its coercive force.

The inner faces of the magnet sections are preferably provided with inclined grooves 6. These grooves are adapted to receive cast aluminum or other non-magnetic metal for locking the magnet sections in position, as will be later described, and the inclination of the grooves is such as to cause the sections to be drawn tightly together.

The sections 4 and 5 comprising each rotor magnet are mounted on the shaft 1 as indicated in Figure 3, but before being so installed their contiguous faces are coated with steel cement 8. By this means an intimate magnetic contact between the two sections of the magnet is provided without the expensive step of machining the sides to provide an accurate mechanical contact.

The magnet 3 is preferably provided with laminated pole shoes 9. The configuration of the laminations is best shown in Figure 3. Each lamination includes an inwardly directed tongue 10 which has a notch 11 formed in each of its opposite edges, and the ends of the laminations are beveled as indicated by reference numeral 12.

The laminations are applied to the assembled magnet sections and then placed in a die and the magnet sections 4—5 as well as the laminations 9 pressed together so as to cause an intimate engagement between their adjacent faces. The molten aluminum or other non-magnetic metal is then poured into the die in the usual way. This metal is indicated generally by the numeral 13, and it will be noted that the metal enters the grooves 6 at the meeting faces of the magnet sections, thus securely and firmly holding the sections with their inner faces in abutting relationship. The grooves 6 are arranged in inclined positions, and it will be obvious that the shrinking of the aluminum as it cools will cause the magnet sections to be drawn tightly together and into intimate contact with the steel cement 8.

The molten aluminum also enters the grooves 11 formed in the edges of the tongues 10 of the laminations, and in this instance also the shrinking of the cast metal as it cools will cause the laminations to be drawn into intimate engagement with the ends of the magnet 3. The cast metal also holds the laminations of each pole shoe in intimate contact, thus avoiding the use of rivets for that purpose, thereby preventing the creation of eddy currents and correspondingly increasing the magnetic value of the magnet.

The flattened portions 2 on the shaft 1 cooperate with portions of the magnet to form elongated channels of segmental cross-sectional shape, and the molten aluminum enters these channels and serves to rigidly anchor the rotor body to the shaft.

The die in which the assembled parts is placed is preferably shaped to provide the integral discs 14 of aluminum, the hubs 15, and a covering 16 for the outer side walls of the magnet sections and the ends of the pole shces.

In the modified construction shown in Figure 6 the sectional magnet 20 is identical with that shown in Figures 1 to 5 inclusive, except that the laminations have been omitted and the sections of the magnet are therefore longer and provided with rounded ends. The means for binding the sections of the magnet together, etc., are identical with those shown in the construction previously described.

From the foregoing description taken in connection with the accompanying drawing it will be apparent to those skilled in the art that I have devised a novel construction of magneto rotor in which the axis of the magnet extends transversely of the rotor shaft; that the magnet sections are intimately bound together in such a way that any machining operations are rendered unnecessary; that the pole shoes are drawn into intimate contact with the poles of the magnet by the shrinking of the cast aluminum; that the bulges formed on the outer walls of the magnet

sections increase the mass of the magnet and consequently its coercive force, and that the cast non-magnetic metal which binds the magnet sections and pole shoes also locks the body of the rotor to the shaft so as to prevent relative movement between the parts.

In accordance with the patent statutes I have described what I now believe to be the preferred form of the invention, but it is to be understood that various changes may be made in the details of construction without departing from the spirit of the invention, and it is intended that all such changes be included within the scope of the appended claims.

What is claimed is:

1. A rotor for magnetos comprising a drive shaft, a sectional magnet composed of two sections of magnetic material, said sections being disposed on opposite sides of said shaft in contact with each other and having inclined notches in their adjacent faces, and a body of cast non-magnetic material interlocking with the walls of said inclined notches to draw the sections into intimate contact.

2. A rotor for magnetos comprising a drive shaft, a magnet mounted on said shaft and having central recesses in its opposite ends, pole shoes for the ends of the magnet, inwardly extending projections formed on the pole shoes midway between their ends and situated in said recesses, and a body of cast non-magnetic interlocked with the projections on the pole shoes for holding the latter in intimate contact with the poles of the magnet.

3. A rotor for magnetos comprising a drive shaft, a magnet mounted on said shaft and having central recesses in its opposite ends, pole shoes for the ends of the magnet, inwardly extending projections formed on the pole shoes midway between their ends and having notches in their side walls, said projections being mounted in the recesses in the magnet, and a body of cast non-magnetic material interlocked with the notches in said projections for holding the pole

shoes in intimate contact with the poles of the magnet.

4. A rotor for magnetos comprising a drive shaft, a sectional magnet composed of two sections of magnetic material, said sections being disposed on opposite sides of said shaft in contact with each other and having inclined notches in their adjacent faces, each end of said magnet being formed with a recess in communication with the inclined notches, pole shoes for the ends

of the magnets, inwardly extending projections formed on the pole shoes and situated in the recesses, and a body of cast non-magnetic material interlocked with the projections on the pole shoes and with said recesses.
